UNITED STATES PATENT OFFICE.

GORDAN MILLER, OF MONETA, CALIFORNIA.

AUTOMOBILE SIGNAL.

Application filed May 14, 1925. Serial No. 30,302.

This invention relates to a signal designed for use on automobiles or self-propelled vehicles.

It is aimed to provide a novel signal having a drum or other element containing all of the necessary signals such as direction signals and a stop signal and further having a license plate or its equivalent associated therewith.

Another object is to provide such a construction wherein the signals are illuminated and the license plate or equivalent is also illuminated so as to comply with modern legislation.

A further object is to provide a novel construction wherein the signals are carried by a drum which utilizes the socket for the illuminating lamp as a bearing.

A still further object is to provide a novel construction of pulley and draw element associated therewith to operate the drum.

Additional objects and advantages will become apparent from a consideration of the description following taken in connection with accompanying drawings illustrating an operative embodiment.

In said drawings:—

Figure 1 is a view in perspective diagrammatically illustrating the control mechanism for a signal and the signal as located on the left rear fender of a vehicle;

Figure 2 is a front elevation of the signal;

Figure 3 is an end elevation of the signal;

Figure 4 is a central longitudinal sectional view through the signal;

Figure 5 is an end elevation of the signal drum particularly showing the pulley thereon; and

Figure 6 is a view of the signal sheet in flat condition to illustrate different signals thereon and their contrasted coloring.

In carrying out the invention, a signal casing is provided at 10 which may preferably be cylindrical as shown, having a closed end wall 11 and being open at the other end and adapted to be closed by a removable end or plate 12, normally held in place by removable screws or bolts as at 13. This casing is preferably disposed on the left rear fender of an automobile as conventionally suggested at F. The casing 10 is secured at this location, with its longitudinal axis disposed transversely of the fender, by means of a bracket 14 which is rigid with the casing 10 and removably bolted or otherwise secured at 15 to the said fender. At

diametrically opposite points at front and rear, the casing is provided with suitably sized window openings 16 preferably covered by glass, celluloid or other transparent panels 17 fastened in place in any appropriate manner.

At the center of the end wall 11 and disposed partly interior of the casing and partly exteriorly of the casing is a metallic lamp socket member 18, rigidly secured in place as by means of solder. Disposed within the casing is a suitable signal drum generally designated 19. This drum consists of a metallic cylinder of skeleton form which is open at one end and at its other end has a wall 20. Rigidly fastened to said wall 20 centrally thereof is a sleeve 21 which extends interiorly and exteriorly of the drum and forms an extended surface which is journaled on the socket member 18 as a bearing, thus journaling the drum for rotation within the casing. Interiorly of the drum a signal member 22 is positioned. This member may be a sheet of normally transparent celluloid or the like having portions thereof formed into signals by having the signal matter painted thereon for instance in black as shown and specifically for instance two "Right" signals with arrows, two "Left" signals with arrows, a "Stop" signal and a license portion or plate 23. It will be noted that the background of the "Right" signal is green, the background of the "Left" signal is yellow and the background of the "Stop" and license signal 23 is red. This sheet in its curled or cylindrical form is held in place within the drum in any suitable manner, for instance by an expansive ring 24 and by a clip 25 which may be a strand of flexible metallic wire passing through apertures 26 in adjacent end edges of the sheet 22 and then having its ends twisted together. It is to be noted that the drum 19 has longitudinal bars which serve to provide longitudinal borders for the different signals. The clip 25 is anchored around one of said bars.

Particular attention is called to the fact that in this signal, a license plate or the equivalent thereof is incorporated by reason of the portion 23, in addition to all of the signals. This gives a very compact arrangement as it enables all signal and license matter to be contained in a single unit.

Fastened against wall 20 as by bolts 27 is a pulley member or ring 28 which at its outer

edge has an outwardly extending marginal flange 29. The wall 20 is the equivalent of a cooperating flange for that at 29. Fastened to the periphery of the pulley ring 28 as by knotting, permitted by openings 30, is a cord, cable or other flexible element having end portions 31 and 32 extending in opposite directions and then through an opening 33 in the bottom of the casing 10, for connection with suitable means to actuate the same and thereby turn the drum. One of the bolts 27 is extended to form a stop 34 which is adapted to engage a suitable stop 35 on end wall 20 and which may be a bolt secured in place by a nut 36. The rotation of the drum is limited in either direction through the engagement of the stops 34 and 35.

In order to illuminate the signal, an electric bulb or lamp 37 is disposed in the inner end of the socket member 18. This bulb is preferably an electric bulb of universal type on the market and likewise the socket member 18 is preferably of universal form so that these parts may be readily and inexpensively acquired for incorporation into the signal and coaction with the parts thereof. The lamp is adapted to be connected to the storage battery of the automobile with which it is associated and as shown is of the "single contact" type in that one side of the lamp is grounded through the casing and socket member.

Normally at the rear window opening 16 the license plate 23 is displayed. If a turn is to be made to the right, one of the cords 31 is pulled which dispose the two "Right" signals opposite the window openings 16. On the other hand if a turn to the left is to be made a pull on the other cable will dispose the "Left" signals opposite said window opening 16. One of the cables is also arranged so that a further pull thereon will dispose the "Stop" signal opposite the rear opening 16. It is to be noted that the "Stop" signal and the license 23 are in diametric alinement and so disposed that when one is in position opposite the rear opening 16, the other is in position at the other opening 16 but inverted so that it will have no effect as a signal.

As one way of operating the cords 31 and

32, they may be passed through an opening 38 in the fender F and then over direction pulleys 38' suitably provided on the automobile. Said pulleys are preferably of the double type as shown so that the operation of one cord will not interfere with that of the other. The cords 31 and 32 are fastened at opposite ends to an arm 39 rigidly carried by a rotatable rod 39' which is disposed along the steering column 40 of the automobile, and fastened thereto and journaled in brackets 41 thereon. The rod 39' may be rocked or rotated in opposite directions through manipulation of a lever 42 fastened thereto and movable with respect to a quadrant 43 which has indications 44 thereon to show the position which the lever 42 should assume when the respective signals are operatively displayed. It will be realized that according to the direction of turning of rod 39', tension will be exerted on the cables 31 and 32, the one not being tensioned, yielding to permit the movement of the other.

Various changes may be resorted to provided they fall within the spirit and scope of the invention.

What is claimed is:—

A signal of the class described comprising a casing, a lamp socket carried by the casing and extending interiorly thereof, a drum within the casing journaled directly on said lamp socket, said drum having a light penetrable signal portion, a lamp within the drum carried by said socket, a pulley on said drum and surrounding said socket, a flexible actuating member operatively associated with the pulley, said casing having an opening through which said operating member extends, said drum having a sleeve extending interiorly thereof for engagement by the lamp and exteriorly thereof to serve as spacing means to provide clearance for the drum and associated parts, said drum being directly journaled on said socket, an element securing said pulley to the drum and serving as a stop, and a stop on the adjacent end wall of the casing to coact with the first mentioned stop to limit the movement of the drum.

In testimony whereof I affix my signature,
GORDAN MILLER.
